[57] **CLAIM**

The ornamental design for a housing for a floor-mounted magnetic contact switch, as shown and described.

DESCRIPTION

FIG. 1 is a pictorial view of a housing for a floor-mounted magnetic contact switch embodying our new design as seen from the upper left rear;

FIG. 2 is a top plan view thereof on a reduced scale;

FIG. 3 is a rear elevational view thereof on a reduced scale;

FIG. 4 is a front elevational view thereof on a reduced scale;

FIG. 5 is a left end elevational view thereof on a reduced scale;

FIG. 6 is a right end elevational view thereof on a reduced scale; and

FIG. 7 is a bottom plan view thereof on a reduced scale.
